(57) **CLAIM**

The ornamental design for an air shroud assembly, as shown and described.

DESCRIPTION

Cross-reference is made to U.S. Non-Provisional patent application Ser. No. 15/407,709 titled, “Parking Cooler” filed Jan. 17, 2017.

FIG. 1 is a front perspective view of an air shroud assembly showing my new design;

FIG. 2 is a front elevation view of the design of FIG. 1; FIG. 3 is a rear elevation view of the design of FIG. 1; FIG. 4 is a first side elevation view of the design of FIG. 1; FIG. 5 is a second side elevation view of the design of FIG. 1;

FIG. 6 is a top plan view of the design of FIG. 1; and, FIG. 7 is a bottom plan view of the design of FIG. 1.

The broken line disclosure represents unclaimed portions of the air shroud assembly in which the design is embodied.
